UNITED STATES PATENT OFFICE.

JOHN HENRY BECKER, OF RICHMOND HILL, NEW YORK, ASSIGNOR TO WARP TWISTING-IN MACHINE COMPANY, OF BROOKLYN, NEW YORK, A CORPORATION OF NEW YORK.

WARP-SUPPORTING MEANS FOR WARP-TWISTING-IN MACHINES.

Application filed January 26, 1928. Serial No. 249,510.

In warp twisting-in machines (see my Patent No. 1,403,067) the upwardly extending warp ends are clamped in carriages which are normally spring-urged horizontally outward as far as a warp-holding means against which the warps bear will permit and move inward when said means is moved inward as the vertically reciprocating structure carrying the carriages moves downward. This invention contemplates certain improvements in the construction of the carriages and of the warp-holding means, designed to lessen the wear on the warps and on the carriages and their guideways, and also in the means by which the movements of said holdings means are effected.

In the drawings,

Fig. 1 is a side elevation of the improved machine;

Fig. 2 is a plan, partly broken away, of its carriage-including superstructure;

Fig. 3 is a front elevation thereof, partly shown in section;

Fig. 4 a rear elevation, with the carriages removed; and

Figs. 5 and 6 details showing the warp-holding means and its actuator.

Except as hereinafter noted the following parts are or may be substantially as heretofore: The frame 1 having fixed bars 2 over which the warps extend toward each other; the vertically reciprocating structure 3 on the top portion of which the warp clamping carriages slide, as will appear, and having a pair of rods 4 to overlie the warps; the fork 5 under and upwardly between whose members the two warps A extend; the twisting mechanism 6 with its thread-severing means 7; the pairs of reciprocating hook-bars 8 adapted to be turned a half-revolution on each outward movement so that each pair, which maintains a lease or cross in each warp, will release the outermost thread thereof; the oscillating finger 9 for separating such threads from their warps so that the spiral 10 can then feed them to the twisting mechanism 6; and the mechanism (partly shown at the right in Fig. 1) for causing the necessary cooperative functioning of those of the foregoing parts which have movement.

Structure 3 has a horizontal arm 11 whose longitudinal opening 11^a contains a pair of

fixed guide-rods 12 on which are springs 13 abutting a fixed block 14. This arm has a pair of top rails 15 and an underneath groove 16. The rails guide the carriages and the groove receives the mentioned warp-holding means.

Each carriage comprises three main parts—a body part, a presser member, together forming a warp-clamp, and a holding clip. The body part 17, having a lug 17^a penetrated by one of the rods 12 and abutted by its spring 13, has a pair of peripherally grooved rollers 18 receiving a top rail 15 and also a pair of rollers 18^a bearing against the lower edge-portion of the arm 11. Thus each carriage is adapted not only to move true and with the least amount of friction but is firmly supported, on account of the tongue and groove connection in effect existing between its rollers 18 and rail 15, against the downward pull of the warps, which is considerable when the machine is in operation and the warps under tension. The presser member 19 is pivoted at 19^a to body part 17 and it and the warp-gripping pads 20 thereof and of the body part are substantially the same as heretofore. The clip 21, pivoted at 21^a, has in its recess 22 which receives the spring lug 19^b affixed to the presser member, a roller 21^b, which without friction rides upon said body when the clip is hooked over the same to cause clamping of the warp.

The warp-holding means comprises a slide 23 which moves in the groove 16 and has its inner end forked and straddling structure 3 and at its outer end has a stop for both warps comprising a shaft 24 fixed in a clip 25 and a roller 26 journaled on each end of the shaft. The rollers engage the warps, and since they are free to rotate they avoid chafing thereof. The inward shifting of the holding means is accomplished by a cam 27 which is formed with a yoke 28 which has a bearing 28^a on the front face of frame 1, the yoke being for this purpose apertured to receive structure 3, and set-screws 28^b to bind against the opposite face; this cam engages the roller 23^a on the slide. Being mounted as described it has a solid and secure connection with the frame.

Having thus fully described my invention, what I claim is:

In a warp twisting-in machine, the com-

bination of the frame, a structure vertically reciprocating therein, a warp-clamping carriage normally urged substantially horizontally along a part of said structure with the tensioned warps depending therefrom, warp-holding means movable horizontally contrary to the carriage, and a cam to move said means on each reciprocation of said

structure, said cam having a jaw bearing against one face of the frame and a screw bearing against the opposite face of the frame and coacting with the jaw to bind the cam to the frame. 10

In testimony whereof I affix my signature.

JOHN H. BECKER.
